UNITED STATES PATENT OFFICE

152,180

DESIGN FOR A LIFT TRUCK

Elmer A. Wagner, Portland, Oreg.

Application June 21, 1947, Serial No. 139,865

Term of patent 14 years

(Cl. D14—3)

To all whom it may concern:

Be it known, that I, Elmer A. Wagner, a citizen of the United States, residing at Portland, in the county of Multnomah, State of Oregon, have invented a new, original, and ornamental Design for a Lift Truck, of which the following is a specification, reference being had to the accompanying drawing, forming a part thereof.

In the drawing Fig. 1 is a right side elevation of the vehicle with the lift portion collapsed; Fig. 2 is a rear elevation of Fig. 1; Fig. 3 is a front elevation of Fig. 1; Fig. 4 is a left side elevation of Fig. 1; Fig. 5 is a plan view of the vehicle; and Fig. 6 is a view in perspective of the vehicle with the lift portion fully extended.

I claim:

The ornamental design for a lift truck, substantially as shown.

ELMER A. WAGNER.
